UNITED STATES PATENT OFFICE.

JOSEPH H. ADAMS, OF FLATBUSH, NEW YORK, ASSIGNOR TO THE TEXAS COMPANY,
OF HOUSTON, TEXAS, A CORPORATION OF TEXAS.

PROCESS FOR THE CONVERSION AND TRANSFORMATION OF LIQUIDS, FLUIDS,
AND OILS.

Application filed March 3, 1919. Serial No. 280,455.

To all whom it may concern:

Be it known that I, JOSEPH H. ADAMS, a citizen of the United States, residing at Flatbush, in the county of Kings and State of New York, have invented a new and useful Process for the Conversion and Transformation of Liquids, Fluids, and Oils, and of which the following is a specification.

This invention relates to an improved method and process for converting high boiling liquid hydro-carbons into products having lower boiling points and specific gravities and particularly for the purpose of obtaining from the heavier and less expensive oils products such as gasolene, naphtha, benzol, toluol and other light oils and oily spirits to augment the natural supply of such products and to meet the great and growing demand for gasolenes and naphthas as fuels for internal combustion engines and for commercial purposes in general.

This process is carried on in an apparatus somewhat similar to that shown and described in my co-pending application No. 530,852, filed Dec. 1st, 1909, now Patent 1,320,354, Oct. 28, 1919, but embodies the features of first volatilizing the oil to be treated, then treating the vapors while they are held under high super-atmospheric vapor pressures within the chamber containing both the oil and oily vapors therefrom, and in addition to this feature the converted vapors are condensed in a condenser connected freely with the cracking chamber in which the vaporization of oil and the cracking of the vapors takes place, so that substantially the same high super-atmospheric vapor pressures are maintained in both parts of the apparatus at the same time during the cracking, transforming and condensing operations.

The apparatus illustrated and hereinafter described was invented by me for use in carrying on the present process but it is not herein claimed since it is made the subject of my co-pending application filed March 3, 1919, Serial No. 280,456.

One object of this invention is to formulate a process of a commercially practical nature for carrying out the above stated conversion, which, to those skilled in the art, is easily distinguished from a mere fractional

distillation process or that of the separation only of the component parts of a hydro-carbon oil by heats sufficient to volatilize the oil without substantial transformation. In this process the temperatures employed are far above the heats necessary for mere oil separation or fractional distillation, and the high super-atmospheric vapor pressures are such as to lend very effectual aid in confining the oil and oily vapors undergoing the change, while at the same time preventing the copious volatilization of oil and condensation of vapors without first being subjected to the intense cracking heats maintained within the vapors for the purpose of transforming them into products essentially different from the original untreated oil.

The nature of the process is such that its full disclosure may be readily understood by describing certain features of an apparatus adapted to carry out the same and by illustrating such features in the several accompanying drawings wherein like characters of reference denote corresponding parts throughout the several views of which:

Fig. 1, is an assembly in elevation of the apparatus as organized for commercially carrying out the process.

Fig. 2, is a vertical sectional elevation showing one of the forms of converter which may be employed for vaporizing oil and then converting the oily vapors within the same chamber.

Fig. 3, is a modified form of converter showing an expansion and separating dome above the vapor cracking chamber and which is an improvement over that shown in Fig. 2.

Fig. 4, is a cross sectional view taken through line Z—Z of Figs. 2 and 3 and shows the relative position of insulator core, electrodes and container.

Fig. 5, shows a battery of improved converters for commercial operation wherein the super-atmospheric vapor pressures are equalized through vapor and oil supply pipes, and:

Figs. 5^a, 6, 7, 8, 9 and 10 show the simple construction of a form of electric heater employed for oil vaporizing and vapor cracking.

Since this invention is of a very simple nature, and before disclosing the operation

of the form of apparatus shown in the drawings, the co-related parts and their relation one to the other may be described so that those skilled in the art may readily understand the process as carried on in this form of apparatus, which is well adapted to carrying out my invention.

Referring now to the drawing Fig. 1. A represents a suitable supply tank, as a source of the oil to be treated. Fluid oil may be admitted to this tank through pipe 1 controlled by valve 2, and the displaced air, at the time of filling, may escape through pipe 3 controlled by valve 4. This tank may be provided with glass sight gauges 5, so that the height of oil therein may be known at all times.

Oil is withdrawn from the tank A, through pipe 6 and sediment trap 7, by pump 8, and forced through pipe 9, precision valve 10 and pipe 11, into a pre-heater B, composed of a refractory brick or asbestos and magnesia lined shell containing a heating means and a pipe coil 12, so that the inflowing oil to the converter may be rapidly heated as it flows through the coils and out through pipe 13 and trap 14, into the body of the converter C—D.

This form of converter is composed of a vaporizing section C, provided with a glass sight gauge 15, to record the height of oil in the section and a thick flint glass sight 16, so that the color of the heater may be observed.

Mounted above the vaporizing section C, and made fast thereto by interposed flange members 41, a section D, is arranged for cracking the vapors of oil arising from the vaporizing section C. This section is provided with a glass sight gauge 17 and a thick flint glass sight 18, so that the color of the vapor cracking heater may be observed.

Leading out from this section D, a pipe 19, connects into the top of a gauge column 20, on which glass sight gauges 21 are arranged so as to enable the operator to more carefully observe the height of oil in the converter C—D. The bottom of this column 20 connects into the top of trap 14 so that there will be a complete circulation of oil and oily vapors through the column and gauge glasses.

Leading out from the opposite side near the top of the section D, a vapor pipe 22, is connected into the upper part of a trap F, in which a baffle plate 23 is arranged to throw down any partially or wholly unconverted vapors before passing out through pipe 24 to the coils 25 of condenser G.

Such heavy vapors which fall in liquid condensate are led back to the section C, through pipe 26, while any lighter partially converted vapors which pass down around the bottom of the baffle plate 23, but which

do not rise and flow out through pipe 24 to the condenser but fall to the bottom of the trap F, flow through pipe 27 to the liquid collecting tank J, to be returned to the tank A, for re-treatment.

The vapors and gases passing through the condenser G, flow through pipe 28, into the distillate and gas collecting tank H, provided with a sight gauge glass 29 and a pressure gauge 30. From this tank the liquid oil is withdrawn through pipe 31 controlled by valve 32, and the non-condensable fixed gases are let off through pipe 33 controlled by needle valve 34.

As it is difficult to regulate the speed of a pump so as to deliver constantly a given fixed quantity of oil to the system, a pipe 35 and an enclosed pop valve 36, are arranged in the oil delivery system from pump 8, and by regulating the tension in the enclosed release valve 36 to a higher pressure than that maintained in the system, the pump 8, can be operated to deliver through precision valves 10, the required amount of oil to the heater and converter, and the surplus oil can be released through this valve and returned to the tank A, for re-circulation. The gauge 37, will record the pressure of oil in the delivery system while gauges 38 at the head of the converter and 30 on the running tank H, will record the back pressure in the system against which the oil must be forced by pump 8 into the converter C—D.

The lower section C, of the converter is provided with a draw-off pipe 39 and valve 40, leading into tank J, so that this section may be emptied and cleared of any heavy oil and sediment which may have accumulated therein and the gauge 34 will indicate the height of oil in this tank.

In this form of apparatus the crown section D, is secured to the lower retort or section C, by flange members 41, which are securely bolted together against a gasket of high heat enduring material. Since the vapors rising into the crown section D, from the body of liquid oil contained in the retort section C, exert a high super-atmospheric vapor pressure, I have arranged a steel cap 42, at the top of this section and made it fast against a gasket by means of strong steel bolts.

As a means of safety in this high pressure system, should an unavoidably excessive pressure occur, a safety valve 43 is provided and arranged in the vapor line 24, above the condenser so that any sudden expansion in the system can be released without affecting the operation of the several co-related parts of the apparatus.

The liquid contents of tank J, can be returned to supply tank A, by means of a pump 45 in connection with pipe 44, provided to withdraw the oil and force it

through pipe 46 into the supply tank so that with new oil it may be re-treated as before.

The heaters contained within the converting retort C—D, and which will be more fully described hereafter, are arranged on conductor rod 47—48, to which electric current is supplied through cables +49 and —50, from a source of low voltage and high amperage, so that the maximum of heat current can be supplied at a comparatively low electro-motive force.

In Fig. 2, a vertical section of the converter shows the interior construction of the vaporizer C and the vapor converter or chamber D. Located within this retort, the two heaters 53 and 54 are held in position by means of the conductor rod 47, —47—48, through which current flows to maintain each heater at the required temperature for their respective operations. It will be noticed that a tube or sheath 55 extends down into the vaporizing chamber C from the flange plate 41, the object being to cause the oil flowing in through pipe 13, to approach the heater 53 from below, as shown by the arrows, and rapidly heat and vaporize. As this sheath is in close proximity to the heater 53, some of the radiated heat therefrom will have the effect of additionally heating the incoming oil contained in the well outside the sheath so that by the time it enters the sheath and surrounds the heater it is raised almost to the point of volatilization.

The vapors rising from the surface of the oil above the heater 53, enters the converting tube or section D, and come in contact with or in close proximity to the heater 54, which is maintained at higher temperature than the vaporizing heater 53. The vapor, in its upwardly passage through the chamber D, is affected within the heated zone and is, in a considerable measure, changed from its higher boiling nature to desirable low boiling products.

These products can be separated out from the condensate by fractional distillation after the converted vapors have passed through pipe 22, the condenser G and into trap tank H, from which they are withdrawn after having been reduced to liquid form.

A feature of importance in an apparatus of this nature is the means for internally applying heat to the oil and oily vapors contained in the retort under high super-atmospheric pressures for the purpose of bringing about the conversion of the high boiling original untreated oil to lower boiling products. Preferably in the apparatus illustrated, this means is electrically operated and comprises one or more resistance rods which are adapted to be maintained at heats designed to bring about the desired results

and which heats must vary with the oils of different gravities and boiling points subjected to transformation by this process.

This electric heater is made up in the form of a grid from a series of resistance rods arranged in pinion like fashion and so connected that the current may flow through them to the best advantage, and while the precise manner of connecting these resistance rods may be varied to conform to different currents of electricity which may be commercially available or generated in connection with this apparatus, the forms shown in Figs. 2 and 4, will be found very suitable for converting many grades of semi-refined and crude oils.

This electric heater is especially adapted for working under an electric current having a relatively low voltage or electro-motive force and a correspondingly high amperage or flow of current which is the heat generating element I propose to employ.

The current is brought in by means of cable or conductor wire +49 and conductor rod 47, which passes through the cap 42 at the top of chamber D, and in order to prevent grounding or short circuit with the metallic parts of the system, an insulator bushing 51, of suitable nonconducting material will be interposed in a tight fitting relation between the cap and a stuffing box or gland 52, provided for the leading in conductor rod 47, so that vapor leakage under high pressure may be avoided.

So also the leading out end of the conductor rod 48, through the bottom of the chamber C, may be provided with an insulator bushing and a gland. The conductor rod 47—48 is divided into three parts, that above the heater 54, and extending out through cap 42, that part connecting heater 54 with 53, and that part extending below heater 53 and out through the bottom of the chamber C. The upper and lower parts of this conductor terminate within the retort C—D, in electrical connection with corresponding terminals of suitably constructed heaters 53 and 54, which comprise one or more heating elements 60, 60^a, 60^b, 60^c, etc., (Fig. 5^a).

These heaters provide means for internally heating the oil and oily vapors so as to very effectively convert the same and assist in performing the steps of primary importance to my process, that is the vaporizing of oil and then transforming the vapors therefrom.

In Fig. 3, a similar sectional view of a retort is shown comprising in addition an expansion dome E. This dome is made fast to the chamber D, by means of a reducing flange 56, and at the upper end of the dome a crowned cap 57, is provided for the attachment of the cap 42, through which the upper part of the conductor rod 48 extends.

Within this dome E, one or more arched perforated baffle plates 58, may be arranged to intercept the vapors before they escape through pipe 22 to the condenser G. The central part of these plates is cut out so as to permit the rod 47-48 supporting the heaters 53 and 54 being removed from the top of the dome when required.

The pieces 59, cut from the central part 10 of the plates 58, are attached to the rod 47-48, in such a position as to close the opening in the large plates 58, when the rod is properly located, but in the drawing these small plates are shown mounted 15 above the larger ones for illustration purposes only, as, in practice, they are so positioned as to form one continuous arched plate for the interception of the heavier vapors.

20 The object of these plates is to collect any partly or wholly unconverted oily vapor and cause it to flow down along the inside of the dome E and reducing flange 56, where it will come into close proximity to the 25 cracking zone or continue down the sides of chamber D, and fall into the chamber C, where it will again be volatilized by heater 53, and eventually become changed when in vaporous form by the heater 54.

30 In Fig. 4, the relative position of the heater rods 60, insulating core 69, sheath 55 and the walls of the chamber C, are shown as well as the inlet pipe 13 and one of the outlet pipes 39.

35 In the erection and operation of the converters, for commercial practice, it is necessary to combine a number of units into a battery so that the supply and discharge to and from them can be handled by one set 40 of supply pipes and the converted vapors by one condensing apparatus, for economy of operation. Such a battery of units is shown in Fig. 5, where three of the converters of the type shown in Fig. 3, are combined with a uniform feed and discharge.

The number of units may be increased to six or even twelve for convenience and economy, and each supply is compensated with the supply to the other converters, by 50 such a pipe as 68, so that a uniform height of oil may be maintained in all of the vaporizing chambers C', C², C³, and any additional ones comprising the battery. In like manner the outlets 22, from the domes E', 55 E², E³, lead up through pipes 70 and down through pipes 71, into one inclined vapor pipe 24, leading to the condenser G, from which they pass into collecting tank H, as described in connection with the apparatus 60 shown in Fig. 1.

I am not herein claiming this liquid or vapor compensation method, however, as that has already been shown and described in my co-pending application Ser. No. 530, 65 852, filed Dec. 1, 1909, now Patent 1,320,354,

Oct. 28, 1919, nor am I claiming the form of heater shown in this application for that appears in my patent 976,975, Nov. 29, 1910, and is fully described in my co-pending application 530,852 already referred to; but 70 for the avoidance of cross reference I will again describe this simple form of heater so that the description may be embodied in this specification.

75 It is, of course, a well known fact that if certain resistant mediums are employed through which an electric current will pass, heat will be generated, and if the material is of a nature to constantly withstand high temperature without breaking down or dis- 80 integrating then a constancy of heat can be depended upon for commercial operation. Such material can be found in a form of graphitic-carbon made in the electric furnace and such carbon can easily be cut, threaded, 85 tapped and shaped into the forms required for this purpose.

The most convenient form for the electrodes will be the round pencils of various 90 thicknesses and lengths threaded at both ends so that attachments can be made as shown in the drawing Fig. 5^A. In this form of grid the heating elements are joined at the top by links as 63 and 65, having nuts 95 of the graphitic-carbon located at both sides of them: while at the bottom the rods or electrodes are screwed into links as 62 and 64, tapped to receive the screw threaded end of the electrode.

100 In order to intercept the current passing in through rod 47 at the top of the unit and cause it to flow through the grid, a core 69, of soapstone, porcelain or other insulating material capable of withstanding temperatures above 1000° F., is provided with 105 metal ends 72, as shown in Fig. 6, and the grid of heating elements is wrapped around this core having the link end 61, at the top, made fast to the part 72 by means of a nut 73, and at the bottom the link 67, is made 110 fast in a similar manner to a corresponding metal part. In this manner the current coming down through rod 47, passes through metal end 72, the link 61, down the rod 60, across the link 62, up the rod 60^a, across the link 63, down the rod 60^b, across the link 64, up the rod 60^c, across the link 65 115 and continues up and down the successive rods and out at the last rod 66 and link 67 to the lower metal part attached to the insulating core 69, and so on to the next heater. The complete heater composed of the core and grid with the metal ends 72, the core 69 and the heating elements 60, is shown at 120 Fig. 7, and in Fig. 8, a top view of the heater is shown while in Fig. 9, a cross section through x-x of Fig. 7, shows the relative position of the core 69 and heating elements 60. Fig. 10, is a view looking down 125 below the line X-X of Fig. 7, and shows 130

the lower link 67, in a position one rod removed from that to which link 61 is attached at the top of the heater.

This form of grid heater can have one or 5 more circles of heating elements and in commercial practice a greater volume of heat is radiated from several circles of smaller diameter heating elements than from a single circle of larger diameter heating elements.

10 It would be impossible to state the exact diameter, the number or the length of rods necessary for the construction of such electric heaters: that being governed entirely by the nature of the resistant medium, the volume 15 of current and electro-motive force, the quality and nature of oil to be converted and the temperature at which the heater is to be maintained. It is sufficient to state, however, that those skilled in the art of 20 electric heater construction can, with the resistant medium available, soon figure out the required parts or near enough so that after a few experiments are made with rods of various sizes and lengths the right electrodes 25 can be combined to form the necessary heaters.

Mode of operation.

Having described one form of apparatus 30 adapted to carry out my process it will be apparent to those having any knowledge of the art that while working under high super-atmospheric vapor pressures there are several things which must be observed in 35 order to obtain the objects sought and to get, as a result of this process, the desired low boiling products without rendering them of inferior nature.

It will be understood from the foregoing 40 description that original oil is contained in tank A, that the pump 8, withdraws the oil from the supply tank and delivers it against a back vapor pressure into the converting and condensing system composed of parts 45 B, C—D—E, F, G and H, and that the surplus oil not forced into the converter is delivered into the tank A, through pipe 35 and enclosed release valve 36, for re-circulation by the pump 8. That the oil so admitted 50 into the system through precision valves 10, is pre-heated in the heater B, then admitted into the vaporizer C, where heat from the electric heater 53, volatilizes the oil, and that such vapors arising from the surface 55 of oil in this container pass up through chamber D, and in close proximity to the heater 54, where the greater part of such vapors are affected by the cracking heat radiated from the resistors and while held 60 under the high super-atmospheric vapor pressures are transformed from high boiling oils into products having lower boiling points and specific gravities.

The vapors so transformed pass out 65 through pipe 22, trap F and into the con-

denser and collecting system G and H, from which latter the liquid product is withdrawn through pipe 31 controlled by valve 32 and the fixed gases through pipe 33 controlled by valve 34. Any condensate not light enough to go over into the condenser, when in vaporous form, is returned to the chamber C or trapped in tank J, from which it is returned to the supply tank A, by means of pump 45 and pipes 44 and 46. 75

In this continuous process the addition of new oil into tank A, is necessary to compensate for the withdrawal of distillates from the running tank H, and so long as the apparatus is operating under favorable 80 conditions with the heaters maintained at uniform heats and the supply and discharge regulated to render the greatest volume of transformed product the process may be continued for days without cessation or disturbance. 85

While this process has a wide range in its adaptability for various purposes and for the treatment of other liquids than hydrocarbons, its mission in this case is to fulfill 90 the need for a method of transforming many of the heavy and inexpensive residue oils into those of greater commercial demand and value to meet the fast growing market necessities, particularly for petroleum spirits, 95 such as gasoline and naphtha.

In the foregoing explanation and in the following claims, mention is made of high super-atmospheric vapor pressures in connection with volatilizing and cracking heats in carrying on the process. From considerable experimenting on an extensive scale and from the practical operation of a large unit producing large quantities of distillates in the operation of this process and where 100 kerosene, gas and solar oils have been employed as the raw materials subjected to transformation, very good results have been had while operating under a vapor pressure above 50 pounds and under 100 pounds to 110 the superficial inch. Pressures which seem to give the best results in large yields of gasoline and naphtha bearing distillates have ranged from 60 to 90 pounds to the square inch and very satisfactory runs of 115 distillate of light color carrying from 80 to 95% of gasoline have been produced while operating under 70 to 80 lbs., pressure to the square inch in the converter and condenser, the light converted vapors rising rapidly from the converter and flowing freely into the condenser, where, under the uniform vapor pressure in the converter and condenser the very light or gaseous parts of the vapors are combined with the 120 heavier parts when condensed under pressure, thus obtaining large yields of higher grade condensate. The pressure is not necessarily limited to 100 pounds to the square inch for in some cases it may be in. 125

creased to three hundred pounds, so that while mentioning satisfactory heats under which cracking has taken place it is not to be taken as limiting the pressures which I may employ in carrying on the process either for hydro-carbon or other liquids which may be treated by employing this process in its broadest possibilities.

The terms "cracking heats" and "cracking temperatures" may be understood and interpreted as temperatures in excess of the necessary heats employed in the processes of fractional distillation of oils or the mere separation of the component parts of a crude or semi-refined oil. Cracking temperatures as applied to petroleum oils may vary from 600 to 1000° F., or even higher, but for commercial purposes in the handling of ordinary residues and the lower gravity oils available for conversion I have found that heats ranging from 700 to 900° F., and vapor pressures of 70 to 90 pounds to the square inch over the surfaces of oils and in the vapors undergoing transformation and condensation give very satisfactory results without, however, using these illustrations in a limited sense.

In the commercial operation of this and all of my former liquid converting processes of record, in apparatus adapted for the several methods, it is the aim, so far as possible, to obtain the greatest yields of that particular product desired at the least cost for fuel and at the lowest pressure, for economical reasons. The heats necessary in oil conversion when ranging above 700 to 800° F., together with pressures from 75 to 100 pounds to the square inch, require apparatus and parts constructed along the lines of boilers and apparatus to withstand 150 pounds steam pressure. This is always within commercial bounds and the possibilities of moderate cost but when large apparatus is constructed to withstand pressures from 100 to 300 pounds to the square inch, that means a strengthening of all parts of the system and which necessarily doubles the cost of an equipment. In addition to that also is the fuel cost to maintain the higher temperatures and while such heats and pressures may be interesting in the experimentation upon the several hydro-carbon oils and other liquids adapted to trans-

formation the actual large yield operation is conducted at temperatures under 1000° F., 55 and pressures below 150 pounds to the superficial inch in the system comprising the pre-heater, vaporizer, converter, condenser and running tank, as the average gravity of oil available in large quantities will range in 60 gravity from 30 to 45° Baumé.

Claims—

1. A process of cracking hydrocarbon oils that consists in applying heat locally to a body of liquid in a combined cracking and 65 vaporizing chamber, applying a cracking temperature locally to the vapors in said chamber, separating the vapors of the heavier and medium products from the lighter products, condensing the lighter 70 products, returning the heavier products to the body of liquid in the cracking chamber, and returning the medium products to the source of supply.

2. A process of cracking hydrocarbon oil 75 which comprises maintaining a body of liquid oil in a combined vaporizing and cracking chamber, confining a localized portion of said body and effecting its vaporization, subjecting the evolved vapors 80 above said body to a cracking temperature, maintaining superatmospheric pressure on the oil under treatment, and withdrawing the evolved cracked vapors.

3. A process of cracking hydrocarbon oil 85 which comprises continuously passing the oil successively through a plurality of series-connected vaporizing and cracking chambers, heating the oil in transit through said chambers to effect its vaporization, locally 90 subjecting the evolved vapors above the oil in the several chambers to sufficient heat to crack the vapors while maintaining a superatmospheric pressure thereon, equalizing the vapor pressure in the several chambers by 95 maintaining a free and open communication between their vapor spaces and withdrawing from the several chambers the vapors concurrently cracked therein.

In testimony whereof I affix my signature 100 in the presence of two witnesses.

JOSEPH H. ADAMS.
